J. KANSTER,

HINGE.

APPLICATION FILED NOV. 27, 1917.

1,311,651.

Patented July 29, 1919.

INVENTOR-

JACOB KAISTER,

BY

H H Dyke
ATTORNEY

UNITED STATES PATENT OFFICE.

JACOB KANSTER, OF NEWARK, NEW JERSEY, ASSIGNOR OF ONE-THIRD TO THOMAS J. WALSH AND ONE-THIRD TO FRANK WALSH, BOTH OF NEWARK, NEW JERSEY.

HINGE.

1,311,651.

Specification of Letters Patent. Patented July 29, 1919.

Application filed November 27, 1917. Serial No. 204,140.

To all whom it may concern:

Be it known that I, JACOB KANSTER, a citizen of the United States, and a resident of Newark, county of Essex, and State of New Jersey, have invented certain new and useful Improvements in Hinges, of which the following is a specification.

My invention relates to hinges. While the hinge of the present invention is more particularly designed for hingedly securing a washtub cover constructed in the manner disclosed in my former Patent No. 1,223,588, granted to me on April 24, 1917, for washtub covers, to a back board, hinges in accordance with the present invention are of general application and may be made use of wherever a strong, substantial hinge is desired.

The object of the present invention is the improvement of hinges in a number of important particulars, as will be hereafter pointed out in my specification and claims, and with the foregoing and related objects in view my invention consists in the parts, improvements, constructions and combinations herein referred to and defined by my claims.

In the accompanying drawing forming part of this specification, and wherein the same reference numerals are uniformly used to designate the same parts throughout, Figure 1 is a plan view showing my improved hinge in use for connecting a washtub cover to a back board. Fig. 2 is a cross-sectional view on line 2—2, Fig. 1. Fig. 3 is a plan view of the hinge member here shown as connected to the washtub cover, the same being shown turned through an angle corresponding to the angle to which such member is turned in Fig. 2. Fig. 4 is a front view of the hinge member here shown connected to the back board, and Fig. 5 is a detail view showing modified forms of openings in one of the tangs of the hinge member shown in Fig. 4.

In the drawing reference numeral 10 is applied to designate the back board which may be secured to the rear side of a washtub or series of washtubs placed side by side, and 11 designates a washtub cover such as disclosed in my former patent above referred to. 12 is the hinge member which in the form shown is secured to the back board 10, and 13 the hinge member secured to the tub cover 11. These members 12 and

13 are formed from sheet metal, as steel and so forth, preferably by stamping operation or operations, and in the form shown the member 12 is provided with a central pintle socket 14, and the member 13 with a pair 60 of pintle sockets 15, 15, one on each side thereof, between which the pintle socket 14 is received and the hinged connection in the form shown is obtained by means of a pintle 16 which is passed through the aligned openings in the sockets 14 and 15, 15. Pintles of various sorts may be used and they may be retained in place in the sockets provided therefor by any suitable means. I prefer to make the pintle 16 of substantially 65 straight cylindrical form as by cutting it off from wire or rod, and when a pintle of such form is used it preferably has a tight fit in the pintle socket 14 and a slightly loose fit in the pintle sockets 15, or vice versa, so that 70 the tub cover or other hinged device can be turned readily and at the same time the pintle will remain in place after insertion except when forcibly removed as by driving it out by means of a punch or other tool. 75 The member 12 is provided with sharpened tangs 17 and 18 which are driven into the object to which the member 12 is to be fastened, here the back board of a washtub cover. The tangs 17 and 18 are integral 80 with the member 12 and in the form shown the tang 17, nearest the pintle socket 14, is formed by stamping out the metal of the member 12, leaving an opening 19 which may be enlarged somewhat beyond the extent of metal bent over to form the tang 17, to provide an opening 19 of pleasing proportions and appearance, and the tang 18 is formed by bending over that end of the member 12 remote from the pintle socket 14, 85 both the tangs 17 and 18 being preferably sharpened to a point so that they may readily be driven into the board or other object to which the member 12 is to be secured. The tang 17 is provided with a hole 20 for 90 the reception of a fastening means, as a nail 21, which is shown as driven through the edge of the back board 10 and through the opening 20, and the member 18 is also provided with an opening 22 which may have 95 the form of a circular hole or may be of other forms as, for example, a slot 22 may be provided which is preferably elongated in a direction parallel to the upper surface of the member 12, or if desired a number of 100

110

openings 22" of circular or other form may be resorted to. Where the nail 21 is driven without special guiding apparatus, the use of slots or of a plurality of holes in the tang 5 18 is preferable as affording better opportunity for the point of the nail 21 to enter the same, but where the nail 21 is driven with the use of a templet or accurate guiding means of any sort, the single hole 22 is 10 ample. The nail 21 extending through the openings 20 and 22 is substantially parallel to the outer surface of the member 12, as will be apparent.

The member 13, here shown as secured to 15 the tub cover 11, comprises a top plate 23 which is provided with an opening 24, a web or body portion 25 and a tang 26 which is provided with an opening 27 alined with the opening 24 in the top plate member 23, 20 which opening 27 may be of circular form or may be of slot form, and if the slot form is resorted to it has its longest dimension preferably parallel to the web 25. In securing the member 13 to the tub cover 11 an 25 opening 28 is preferably formed in the metal 29 of the tub cover at the rear edge thereof, through which the tang 26 is driven into the wooden frame 30 of the tub cover, and a fastening member, as a nail 31, is passed, as 30 by driving, through the alined openings 24 and 28, and if a nail is used it is preferably of such length as to clench, as shown at 32, on being driven home, against the metal plate 33 on the bottom of the cover frame 35 30. The nail 31, when in place, is substantially at right angles to the top plate 23 of the hinge member 13, and the two nails 21 and 31 are substantially at right angles to one another in the normal closed position of the 40 hinged members. The top plate 23 may also be formed as a tang and be driven into the wood, and various other modifications may be made.

It will be seen that numerous advantages 45 are secured with a hinge constructed in accordance with my invention. The hinges may be made from sheet metal by a simple stamping operation or operations, the material used is inexpensive and where material such as steel is used, which might 50 rust on continued exposure to dampness, as in the case of use as a tub cover, it may be readily protected by being given a suitable coating, as by being dipped in a galvanizing bath of the like, they may be securely and strongly fastened to the members to which they are to be attached, as the tub 55 cover and back board, by simple driving operations, entirely dispensing with the use 60 of screws which are expensive, and by being provided with the alined openings into which nails or other fastening members are driven, they are strongly and securely held

and cannot work loose, the exposed portions thereof present a novel and pleasing appearance and a great saving and economy of time is secured by the mode of fastening the improved hinge in place, it being possible, for example, for a workman to secure and assemble several times as many of the 70 hinges in accordance with the present invention as can be done in the same time with the ordinary form of flat hinge fastened into place by screws.

It will be understood that the embodiment 75 of the invention which has been shown and described is intended for the purpose of affording a clear understanding of my invention only, and that I am not to be confined to such specific embodiment, but may 80 resort to numerous modifications and changes within the scope of my claims without departing from my invention or sacrificing the advantages thereof.

I claim:

1. A struck up sheet metal hinge, a member whereof is provided with a plurality of sharpened tangs located at a substantial distance apart, and said tangs being provided with substantially alined openings. 90

2. A struck up sheet metal hinge, one of the members whereof has sharpened tangs provided with substantially alined openings, and the other member whereof is provided with a sharpened tang and a surface 95 plate, said tang and surface plate having substantial alined openings.

3. A struck up sheet metal hinge, one of the members whereof comprises a surface plate and a pintle socket and two separate 100 integral tangs extending at right angles to the surface plate, one of said tangs being adjacent to the pintle socket and struck out of the material of the face plate and leaving an opening therein, and the other being 105 at the end of the face plate remote from the pintle socket, said tangs having substantially alined openings therein adapted to receive a nail driven substantially parallel to the face plate, and the other member whereof 110 comprises a surface plate, a web and a tang, the tang extending substantially parallel to the surface plate, and said surface plate and tang being provided with substantially 115 alined openings therein to receive a nail driven substantially at right angles to the surface plate, and said member having a pair of pintle sockets between which the pintle socket on the other member of the hinge is adapted to be received, and a pintle 120 passing through the alined pintle sockets.

In testimony that I claim the foregoing, I have hereto set my hand this 23rd day of November, 1917.

JACOB KANSTER.
